HOISTING MECHANISM

Paul F. Blackman, Edwin N. Blackman, and Jan W. Shipp, Los Nietos, Calif.; said Edwin N. Blackman and said Jan W. Shipp assignors to said Paul F. Blackman

Application July 6, 1948, Serial No. 37,246

2 Claims. (Cl. 212—8)

1

The present invention relates to an improved hoisting arrangement particularly useful, but not limited in its use, in loading and unloading heavy objects from a truck.

An object of the present invention is to provide an improved winch-operated loading device especially useful in oil field work.

Another object of the present invention is to provide an improved hoisting mechanism characterized by its simplicity and adaptability so that it may be operated with a minimum personnel to advantage wherever the moving of heavy objects by truck is desired.

Another object of the present invention is to provide an improved hoisting mechanism which may be operated by but one person to load and unload tools, drilling equipment, engines, etc., in oil field operations.

A further object of the present invention is to provide an improved hoisting mechanism comprising relatively few parts which may be easily manufactured and assembled by the use of present-day mass production methods and expedites.

A further object of the present invention is to provide an improved hoisting mechanism in which the stress carrying members are subjected substantially only to tension and compression forces in hoisting operations with substantially no bending forces on such members.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a view of a hoisting mechanism mounted on a truck in operative position to raise an object from the ground onto the truck platform upon which the mechanism is mounted.

Figure 2 is a view similar to the view shown in Figure 1 but with the mechanism in position when the object is raised above the ground.

Figure 3 is a view similar to the view shown in Figure 1 with the parts of the hoisting mechanism in position after such object is placed on the truck platform.

Figure 4 is an elevational view showing the hoisting mechanism in its lower position in solid lines and in its upper position in dotted lines illustrating the manner in which the parts move relative to each other.

2

Figure 5 is a sectional view taken substantially on the line 5—5 of Figure 4.

Figure 6 is a view in elevation taken in the direction indicated by the arrows 6—6 in Figure 4.

Figure 7 is an enlarged cross-sectional view taken substantially on the line 7—7 of Figure 4.

Figure 8 is a view similar to Figure 7 and shows the manner in which the hoisting parts are maintained in the position shown in Figure 3.

The hoisting mechanism comprises a frame which includes a center leg 1 and two side legs 8, 9 each pivotally connected to the truck deck or platform P at 7A, 8A, and 9A, respectively. The center leg 1 comprises in fact an inner telescopic member 11 which is pivotally connected at 7A and an outer telescopic member 12 which has a sheave block 13 mounted on its upper end. The inner telescopic member 11 is referred to as a boom. This sheave block 13 is pivotally connected to the upper ends of the side legs 8, 9. Outward movement of the outer sleeve member 12 is prevented by the stop member 10 mounted on the upper end of the inner telescopic member 11. The length of the outer center leg 12 determines, as will be more evident as this description progresses, the horizontal travel of the sheave block 13 over the deck P of the truck.

The sheave assembly 13 consists of a steel bronze bushed wheel 13A, and the block 13B is of steel plate welded to the upper end of the outer center leg 12. The wheel 13A is held in position and rotates on the same steel pin 13C which secures the side legs 8, 9 to the sheave block 13B.

The outer sleeve member 12 is adapted to contact the ring 15 in its downward movement on member 11 to compress the coil buffer spring 16 which is suitably housed in the hollow cylindrical casing 16A mounted on the inner member 11. Such downward movement of the outer sleeve member 12 is limited when the ring member 15 having the integrally formed cylindrical portion 15A engages the inner casing wall at 16B. This cylindrical portion 15A thus cooperates with the wall at 16B to form a stop preventing excessive compression of the spring 16 when the outer sleeve member 12 is moved downwardly. This spring 16 is a heavy duty compression spring and serves to cushion the shock on this hoisting mechanism in loading and unloading operations and also to start movement of the load in the initial stage of the unloading operation as will be described in more detail hereinafter. Normally, this compression spring 16 is prestressed

to normally urge the outer sleeve member 12 against the stop member 10 on the inner sleeve member 11.

A flexible cable 20 passes over the rotatable element or wheel 13A in the sheave assembly 13 and also over the power-driven winch 21. This winch 21 may be of conventional structure and may be driven in conventional manner and is rotatably supported on the truck platform. This cable 20 has mounted thereon an abutment or stop 22 arranged to cooperate with the re-entrant portion 23 in the sheave block to produce relative movement of the outer sleeve member 12 with respect to the inner sleeve member 11, as is described in more detail hereinafter.

Referring to Figure 1, in the initial stage of the loading operation the winch drum is operated to wind the flexible cable 20 thereon, the free end of the cable 20 being, of course, attached to the apparatus A which is to be hoisted onto the platform P of the truck. When and as the cable 20 is taken in by the winch, the object A travels vertically until the stop member 22 on the line 20 contacts the re-entrant portion 23 of the sheave block. Thereafter, the sheave assembly 13 mounted on the outer telescopic member 12 is moved toward the front of the truck, causing the inner center leg 11 to raise while the outer center leg 12 follows the same arc as the side legs 8, 9 to thereby cause the load or object A to travel in a general horizontal path over the bed of the truck. During such movement of sleeve member 12 on the inner member 11 the coil compression spring 16 is progressively stressed and serves as a buffer to absorb any shock forces. When the outer sleeve member 12 moves the required distance to position the object A over the platform P of the truck, the operator inserts a removable pin 30 through matched or aligned holes 11S, 12S in the telescopic members 11, 12, respectively, to thereby maintain the compression spring 16 in its compressed state to allow subsequent slackening of the cable 20 and lowering of the object A onto the platform P of the truck.

To thereafter unload the object A from the platform of the truck onto the ground, the winch is operated to raise the object A and to bring the stop member 22 in engagement with the re-entrant portion 23 of the sheave block after which the pin is withdrawn from the aligned holes 11S, 12S whereupon the stored energy in the spring 16 causes the outer sleeve member 12 to move outwardly on the inner sleeve member 11, simultaneously moving with it the object A to a position where the object A may be directly loaded onto the ground; this position corresponds to the position wherein the outer sleeve member 12 contacts the stop member 10 to limit such outward movement. When the outer sleeve member 12 thus engages the stop 10, the mechanism is in the down position and the load A may then be lowered onto the ground or a loading dock by releasing the winch.

In the normal position, as shown in Figure 1, it is noted that the inverted V-shaped frame comprising the frame members 8, 9 having the sheave assembly 13 pivotally mounted at the apex of said V-shaped frame has gravity forces acting thereon tending to rotate such sheave away from the truck bed about the pivotal connections 8A, 9A, but such movement of the sheave which would otherwise be produced by gravity forces acting thereon, is limited by the cooperating stop means 10 interposed between the rela-

tively movable telescopic members 11, 12. Thus, the frame members of the hoisting mechanism in Figure 1 are normally maintained in position shown therein by the action of gravity forces 5 acting on the frame members and without any action of the coil compression spring 16 which only becomes compressed during the final stage of the loading operation.

While the particular embodiments of the present invention have been shown and described, it will be obvious to those skilled in the art that changes and modifications may be made without departing from this invention in its broader aspects and, therefore, the aim in the appended 15 claims is to cover all such changes and modifications as fall within the true spirit and scope of this invention.

We claim:

1. A hoisting mechanism comprising a single 20 pair of elongated side frame members, a sheave assembly incorporating a rotatable member, a support, said frame members being each arranged to have one of its ends pivotally mounted on said support and its other end pivotally connected to said sheave assembly, a centrally disposed pair of telescopic members centrally mounted with respect to said side members, the outer one of said telescopic members being affixed to said sheave assembly, the inner one of 25 said telescopic members being arranged for pivotal movement on said support, a flexible cable passing over said rotatable member and through said sheave assembly and having a stop member thereon for engagement with said assembly, said cable having a reach extending generally parallel with said pair of telescopic members, and power operated means to reel in said cable to thereby move said stop member into engagement with said sheave assembly to move said 30 assembly with respect to the inner one of said telescopic members, said inner one of said telescopic member extending all the way through said outer telescopic member and having an enlarged stop member thereon cooperating with 35 that end of the outer telescopic member which is adjacent said sheave assembly.

2. A hoisting mechanism comprising a single 40 pair of elongated side frame members, a sheave assembly incorporating a rotatable member, a support, said frame members being each arranged to have one of its ends pivotally mounted on said support and its other end pivotally connected to said sheave assembly, a centrally disposed pair of telescopic members centrally mounted with respect to said side members, the outer one of said telescopic members being affixed to said sheave assembly, the inner one of 45 said telescopic members being arranged for pivotal movement on said support, a flexible cable passing over said rotatable member and through said sheave assembly and having a stop member thereon for engagement with said assembly, said cable having a reach extending generally parallel with said pair of telescopic members, and power 50 operated means to reel in said cable to thereby move said stop member into engagement with said sheave assembly to move said assembly with respect to the inner one of said telescopic members, said inner telescopic member having mounted thereon a hollow cylindrical casing, a buffer spring encircling said inner telescopic member and disposed within said casing, a ring encircling 55 said inner telescopic member and disposed between, on the one hand, said spring, and on the other hand, said casing, said ring being adapted 60

70 75

for contact by the outer telescopic member, a cylindrical portion affixed to said ring and co-operating with an end wall of said casing to prevent undue stressing of said spring.
